UNITED STATES PATENT OFFICE.

THOMAS ARCHER, JR., OF GATESHEAD-ON-TYNE, ENGLAND.

ORE-CRUSHER.

SPECIFICATION forming part of Letters Patent No. 340,472, dated April 20, 1886.

Application filed February 24, 1885. Serial No. 156,849. (No model.) Patented in England November 25, 1884, No. 15,521; in Germany February 1, 1885, No. 32,636; in France February 12, 1885, No. 166,996, and in Belgium February 14, 1885, No. 67,889.

To all whom it may concern:

Be it known that I, THOMAS ARCHER, Jr., engineer, a subject of the Queen of Great Britain and Ireland, residing at Dunston Engine Works, Gateshead-on-Tyne, England, have invented certain new and useful Improvements in Ore-Crushers, (for which I have obtained Letters Patent in the following countries, to wit: Great Britain, No. 15,521, dated November 25, 1884; France, No. 166,996, dated February 12, 1885; Belgium, No. 67,889, dated February 14, 1885; Germany, No. 32,636, dated February 1, 1885,) of which the following is a full, clear, and exact description.

15 The invention relates to that class of ore-crushers wherein a movable jaw is vibrated in proximity to a fixed jaw for the purpose of crushing the material fed between them, and in order that it may be fully understood it will 20 be described with reference to the accompanying drawings, in which—

Figure 1 is a sectional elevation of an ore-crusher embodying the invention. Fig. 2 is a vertical transverse section thereof on the line 25 A B, Fig. 1. Fig. 3 is a detail view of the operating-cam, the end of the operating-lever, and the anti-friction roller carried thereby.

C is the framing of the machine, which may be of any suitable character, and D the fixed 30 jaw supported thereby.

E is the movable jaw, which depends from an axis or trunnions, e, supported by the frame C in such a manner that the said jaw E can be vibrated upon its said axis or trunnions. F 35 is a lever by which this vibration is effected, said lever being fulcrumed at one end upon an axis, f, supported by the framing of the machine, and provided at the other with an anti-friction roller, f³, which rests upon a cam or eccentric, G, carried by the main shaft H of the machine.

The cam G is shown in the drawings as being formed with two rises, so as to vibrate the lever F twice during each revolution of the 45 shaft H; but this may be varied at will. For example, it may have only one rise, whereby

the lever F will be vibrated once by each revolution of the shaft H; or it may have more than two, with a corresponding increase in the number of vibrations imparted to the lever F by each revolution of the shaft H.

Between the back of the movable jaw E and the adjacent part of the lever F is interposed a toggle or thrust piece, I, said thrust-piece being situated nearer the lower extremity of the jaw E and somewhat above the center of oscillation of the lever F, whereby said jaw E is made to approach the fixed jaw D each time the free extremity of said lever F is elevated. The return movement of the jaw E is effected partly by gravity, but principally by spring k, which bears at one end against a fixed part of the frame C and at the other against a collar or cross head secured to a rod, j, whose extremity is connected to the rear side of said jaw. The tension of this spring may be regulated by a nut, l, which is held to place by a lock-nut having a weighted handle, m, whereby it is prevented from turning off.

Having thus described my invention, the following is what I claim as new therein and desire to secure by Letters Patent:

In a machine for crushing ores, the combination, with the frame C, having the fixed jaw D, of the movable jaw E, hinged at top, the 75 vibrating lever F, fulcrumed at one end and provided with an anti-friction roller, f³, at the other, a thrust or toggle piece, I, interposed between the back of the movable jaw and the adjacent face of the lever F above its fulcrum, 80 the operating-shaft, H, having cam G, the rod j, and the spring k, all constructed and arranged to operate substantially as set forth.

In testimony whereof I have signed my name to this specification in the presence of 85 two subscribing witnesses.

THOMAS ARCHER, JR.
